SHOE GLUING STAND

John Frank Settile, Kingston, N. Y.

Application April 20, 1937, Serial No. 138,044

3 Claims. (Cl. 12—123)

My invention relates generally to shoe making and repairing apparatus, and particularly to a stand for use in gluing and cementing soles, in the repair and replacement of shoe soles, and an important object of my invention is to provide an arrangement of this character which is especially adapted to the work, and which enables rapid and efficient repairing.

Other important objects of my invention will be apparent from a reading of the following description taken in connection with the drawings, wherein for purposes of illustration I have shown a preferred embodiment of my invention.

In the drawings:—

15 Figure 1 is a general side elevational view of the embodiment.

Figure 2 is an elevational view of Figure 1 looking from left to right.

Figure 3 is a longitudinal vertical sectional view taken through Figure 1.

20 Figure 4 is a transverse vertical sectional view taken through Figure 3 approximately on the line 4—4 and looking toward the right in the direction of the arrows.

25 Figure 6 is a horizontal sectional view taken through Figure 3 approximately on the line 6—6 and looking downwardly in the direction of the arrows.

Figure 7 is a bottom plan view of one of the 30 replaceable lasts.

Referring in detail to the drawings, the numeral 5 generally designates a pedestal having a suitable foot or base 6 provided with an opening 7 to receive a bolt or screw for attaching the 35 base to a supporting surface 8. The pedestal includes the column 9 and the generally triangular brace 10 extending from one side of the column. On and affixed to the top of the column and the top of the brace 10 is the generally rectangular elongated horizontally disposed body 11 which has an elongated rectangular opening 12 in its top and extending only through one end of the body, the opposite end of the recess 12 being closed by the back wall 13.

45 Slidably resting in the recess 12 is a conformably shaped slide block 14 which has at its front end a depending portion 15 and at its opposite end a standard 16 which has a curved aperture 17 in its upper end which is lined by material 50 18 suitable to provide a non-injurious rest for the toe portion of a shoe (not shown).

Threaded in the body 11 near the front end thereof is the rod 19 which is fixedly inserted in a replaceable last 20 as indicated by the numeral 55 21, and this rod 19 extends upwardly through an

elongated longitudinally disposed slot 22 which is formed in the slide block 14.

By providing a number of the lasts 20 with the threaded rod 19 attached thereto as indicated, in the required number to accommodate the different sizes of shoes to be mended and soled, the correct size for the particular shoe to be worked upon can be selected and placed in position simply by screwing its rod 19 into the threaded hole in the body 11. The last is assembled in an up-side-down position as indicated in the drawings, with the shoe thereon, and the toe portion of the combined shoe and last is rested on the aperture 17, so that the shoe is then positioned to be worked upon for a repair or replacement of the sole. This arrangement is especially and particularly adapted to the operation of re-soled in which the sewed or nailed sole is first removed either in whole or in part, or left in place, and a composition sole then applied and cemented or glued in place. As this procedure is now carried on, the shoemaker must first apply cement or glue to the shoe and then put the shoe down, and then apply glue or cement to the sole, and then put this down, and subsequently bring both together, in a clumsy and inefficient and hit-and-miss manner, resulting in a poor job, at the expense of much time and labor. Whereas, using the device of the invention, the shoe is constantly in place, and when the same has had the cement applied thereto and the sole is ready for application, the shoe stands in a steady and correct position and application of the sole thereto is a simple and easy operation. It will be obvious that the slot 22 permits the 25 slide 14 to be moved to a position to accommodate different sizes of lasts.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

What is claimed is:—

1. A shoe sole gluing stand comprising a base having a column rising therefrom, a block on the upper part of said column and formed with a longitudinal groove, a slide mounted in said groove and having a standard rising therefrom, said slide being formed with a slot, an inverted shoe last having a rod depending therefrom and through said slot, and means removably mounting said rod on said block with the 50 55

toe portion of the last overlying the top of said standard.

2. A shoe sole gluing stand comprising a support, an inverted shoe last supported above said support, a standard on whose upper end the toe part of said last is to rest during gluing operations, a base for said standard underlying the last, and means adjustably mounting said base on said support to accommodate different sizes 5 of lasts.
3. A shoe sole gluing stand comprising a sup-

port, an inverted shoe last supported above said support, a standard on whose upper end the toe part of said last is to rest during gluing operations, a base for said standard underlying the last, and means adjustably mounting said base on said support to accommodate different sizes of lasts, said means comprising a recess in the upper surface of the support within which the base is 10 slidably positioned.

JOHN FRANK SOTTILE. 10
